UNITED STATES PATENT OFFICE.

BRUNO STECHBArt, OF CHICAGO, ILLINOIS, ASSIGNOR TO AMERICAN PROJECTING COMPANY, OF CHICAGO, ILLINOIS, A CORPORATION OF DELAWARE.

MOTION-PICTURE MACHINE.

1,334,324.

Specification of Letters Patent. Patented Mar. 23, 1920.

Application filed May 21, 1919. Serial No. 226,591.

To all whom it may concern:

Be it known that I, BRUNO STECHBArt, a citizen of the United States of America, and a resident of Chicago, in the county of Cook, 5 State of Illinois, have invented certain new and useful Improvements in Motion-Picture Machines, of which the following is a specification.

This invention relates to that class of in- 10 cased motion picture machines, such as constitutes the subject matter of my prior Letters Patent No. 1,287,503, dated December 10, 1918, and in which the film supporting and operating mechanisms are mounted in 15 a shell or housing as a complete and assembled unit for attachment within the main inclosing casing of the machine. And the present improvement has for its object:—

To provide a simple, compact and ef- 20 ficient structural formation and association of parts wherein the driving motor of an electric type, with its reversing switch are mounted as a part of the above mentioned assembled unit, and adapted to afford a 25 power driven means for winding and un- winding the picture film upon the companion film reels of the machine, all as will hereinafter more fully appear.

In the accompanying drawings:—
30 Figure 1 is a detail side elevation illustrating the general structural arrangement of the present improvement as applied to the motion picture machine shown in my aforesaid Letters Patent No. 1,287,503, parts 35 of the supporting shell or housing being broken away to show the arrangement of the reversing switch of the electric motor.

Fig. 2 is a detail front elevation of the shell or housing and associated electric 40 motor and its reversing switch.

Fig. 3 is a fragmentary longitudinal section on line 3—3, Fig. 2.

Like reference numerals indicate like parts in the several views.
45 Referring to the drawings, 1 designates a portion of the front wall of the main inclosing box or casing of a portable motion picture machine, to the inner face of which is secured an inclosing shell or housing 2 in which is mounted and contained the picture film guiding and actuating means and mechanisms, as well as the light controlling shutter of a machine, such as described in 50 my aforesaid Letters Patent No. 1,287,583.

3 designates the transversely arranged 55 primary driving shaft of the above mentioned mechanisms, provided at one end with the usual driving pulley 4, preferably of the heavy fly wheel type as shown.

5 designates a vertically disposed en- 60 larged portion of the shell or housing 2, providing a shallow containing chamber for the light shutter of the machine as set forth in my former Letters Patent No. 1,287,503, and in the present construction:— 65

6 designates an enlarged open front portion of the shell or housing 2, arranged forward of the aforesaid enlarged portion 5 and adapted to provide a containing chamber for the reversing switch 7 of the electric 70 motor 8 used as the driving means of the machine.

9 designates a depending portion of the aforesaid enlarged front portion 6, formed at its lower end with a curved flange 10 75 forming a seat for the shell of the motor 8, which is secured in place by screw bolts 11, as shown in Figs. 2 and 3.

The reversing switch 7, above referred to, may be of any usual type, preferably of the 80 semi-rotary snap switch type shown, and having a handled operating shaft 12 disposed in a sunken socket plate 13 in the front wall of the main casing 1 for convenient manual operation.

14 designate line wires or conductors be- 85 tween the reversing switch 7 and the electric motor 8, arranged in the chamber of the aforesaid front portion 6 of the shell or housing 2.

15 designates a pulley mounted on the armature shaft of the electric motor 8 and having an endless belt connection 16 with the pulley 4 of the aforesaid primary shaft 3 of the film actuating mechanism. 95

17 designates a spring actuated belt tightener, the carrying arm 18 of which is pivoted to the depending shell portion 9 of the shell or housing 2 aforesaid.

Having thus fully described my said in- 100 vention what I claim as new and desire to secure by Letters Patent, is:—

1. In a motion picture machine, the combination of a shell or housing forming a sup- 105 port for a film actuating mechanism and its primary driving shaft, said shell having a seat on its under side, a motor having an inclosing shell attached to said seat, and op-

erative connections between the shaft of said motor and the primary shaft aforesaid, substantially as set forth.

2. In a motion picture machine, the combination of a shell or housing forming a support for a film actuating mechanism and its primary driving shaft, said shell having an open front containing chamber and a seat on its under side, a reversing switch arranged in said open front chamber, a motor having an inclosing shell attached to said seat, and operative connections between the shaft of said motor and the primary shaft aforesaid substantially as set forth.
3. In a motion picture machine, the combination of a shell or housing forming a support for a film actuating mechanism and its primary driving shaft, said shell having an enlarged front portion the lower depending part of which is formed with a seat, a motor having an inclosing shell attached to said seat, and operative connections between the shaft of said motor and the primary shaft aforesaid substantially as set forth.
4. In a motion picture machine, the combination of a shell or housing forming a support for a film actuating mechanism and its primary driving shaft, said shell having an enlarged front portion the lower depending part of which is formed with a curved flange, a motor having an inclosing shell at-

tached to said flange, and operative connections between the shaft of said motor and the primary shaft aforesaid, substantially as set forth.

5. In a motion picture machine, the combination of a shell or housing forming a support for a film actuating mechanism and its primary driving shaft, said shell having an enlarged front portion forming a containing chamber and with a seat on its lower depending part, a reversing switch arranged in said containing chamber, a motor having an inclosing shell attached to said seat, and operative connections between the shaft of said motor and the primary shaft aforesaid.

6. In a motion picture machine, the combination of a shell or housing forming a support for a film actuating mechanism and its primary driving shaft, said shell having an enlarged front portion forming a containing chamber and with a curved flange on the lower depending part of the same, a reversing switch arranged in said containing chamber, a motor having an inclosing shell attached to said flange, and operative connections between the shaft of said motor and the primary shaft aforesaid, substantially as set forth.

Signed at Chicago, Illinois, this 30th day of April, 1919.

BRUNO STECHBART.
